UNITED STATES PATENT OFFICE

IVAN RODIONOVITCH AFONIN, OF LONDON, ENGLAND

LIQUID-STORAGE TANK

Application filed July 2, 1928, Serial No. 289,912, and in Great Britain July 6, 1927.

This invention relates to liquid storage tanks of the type having a floating roof, and more particularly to tanks of the type in which the roof is divided into a plurality of 5 flexibly connected cells.

According to this invention one or more open containers for rain or other water is or are provided on the upper surface of the floating roof. In the case of a cellular roof means 10 are also provided for preventing the water from finding its way into the tank between two adjoining cells.

The invention as applied to a cellular roof is illustrated by way of example in the annexed drawings, in which:—

Fig. 1 is a partial plan.

Fig. 2 is a section on the line 2—2 of Fig. 1.

Fig. 3 is a detail on an enlarged scale, and

Fig. 4 is a side view of a further detail.

As shown in the drawings, the water containers are formed with plain vertical side walls *a* opposite to which on adjacent cells *x* are arranged other walls *b* which are bent as shown in Figs. 2 and 3 to form hoods which extend over the upper edge of the walls *a* and prevent the entry of water between two adjacent cells *x*.

At the corners where four cells abut a sliding cover plate *c*, which is preferably octagonal, rests on the upper surface of the hoods *b*, as shown in Figs. 1 and 4.

Although the containers are usually supplied with rain water they may, if desired, be supplied with water from any convenient source, which may also be used at any time to ensure that the level of the water is approximately the same in all the containers in order to prevent any particular cell from tilting relatively to the others.

Having thus described the nature of my said invention and the best means I know of carrying the same into practical effect, I claim:—

1. A floating roof for liquid storage tanks comprising a plurality of cells each having walls projecting upwardly therefrom and forming water containers, some of said walls being bent outwardly and downwardly to extend over adjacent unbent walls of adjacent cells.

2. A liquid storage tank, a cellular floating roof for said tank, a plurality of water containers located on the upper surface of said roof, said cells supporting bent walls which form hoods for plain vertical walls of adjacent containers, and a sliding plate resting on the upper part of each hood at corners where more than two cells meet. 55

In testimony whereof I have signed my name to this specification.

IVAN RODIONOVITCH AFONIN. [I. S.] 60
